UNITED STATES PATENT OFFICE.

JAMES C. DOZIER AND JOSEPH L. WALKER, OF BATON ROUGE, LOUISIANA.

VENEER-SLITTING MACHINE.

1,356,271.

Specification of Letters Patent. Patented Oct. 19, 1920.

Application filed March 10, 1920. Serial No. 364,839.

To all whom it may concern:

Be it known that we, JAMES C. DOZIER and JOSEPH L. WALKER, citizens of the United States, and both residing at Baton Rouge, in the parish of East Baton Rouge, and State of Louisiana, have invented certain new and useful Improvements in Veneer-Slitting Machines, of which the following is a specification.

This invention relates to certain new and useful improvements in machines for slitting veneer or thin material into strips.

The present invention is designed primarily as an improvement upon the machine for this purpose which forms a subject matter of Patent No. 1,234,884 granted to us July 31, 1917.

The construction shown in the aforementioned patent while most efficient for the purposes for which it has been employed, has been found to be capable of improvement to meet new requirements, such for instance as dividing three-ply veneer which requires more powerful feed than can be obtained from the construction shown in the said patent. In slitting three-ply veneer it is very desirable, if not absolutely necessary, that the stock be cut on both sides simultaneously.

The present invention has for a primary object the dispensation of the bed plate or table employed in the construction shown in the prior patent, and in so constructing and arranging the bottom knife holder, or holders, that the upper end or ends thereof shall furnish all the bed plate that is necessary to support the material against the cut of the upper knife or knives. This greatly simplifies the construction and enables us to economize space and to provide better support for the knife bars, which support serves to materially strengthen the framing of the machine.

We aim further at the improvements in the details of construction whereby provision is made for adjusting the heads or knife holders to any width, as circumstances may require.

Other objects and advantages of the invention will hereinafter appear and the novel features thereof will be particularly pointed out in the appended claims.

The invention, in its preferred form, is clearly illustrated in the accompanying drawings, which, with the numerals of ref-

erence marked thereon form a part of this specification and in which:

Figure 1 is a side elevation of our improved veneer slitting machine.

Fig. 2 is a substantially central vertical longitudinal section through the same.

Fig. 3 is an enlarged vertical longitudinal section through the knives and their holders with portions of the adjacent feed rolls broken away.

Fig. 4 is an end view of one of the knife holders and knife, with portions broken away.

Fig. 5 is a vertical section through one of the knife holders showing the knife cap in position.

Fig. 6 is a detail in elevation with portions broken away, looking in the direction of the line of feed of the material to be slit.

Fig. 7 is a section taken at right angles to Fig. 5.

Fig. 8 is an end elevation with portions broken away.

Fig. 9 is a top plan.

Like numerals of reference indicate like parts throughout the different views.

Referring to the drawings, 1 designates a bed or base of any suitable character supported in any desired way as by the legs or supports 2, the same being of substantial construction so as to firmly support the operating parts now to be described.

As before noted, in the present construction, we employ no table or bed plate for the support of the material being acted upon, but in lieu thereof we support the knife holders and their accessories intermediate the center feed rolls and have the upper end of the bottom knife holder serve in lieu of such table or bed plate. For this purpose we provide the castings or standards 3 which are firmly bolted or otherwise affixed to the base 1 and to the top housing 4 as clearly shown in Figs. 1 and 2.

5 are guide rods mounted in the top housing or cap plate 4 and in the base 1, and these rods serve to support the tubular bearings 6 and 7 for the upper and lower sets of feed rolls as will be clearly understood upon reference to Fig. 2. The lower bearings may be adjusted vertically by means of the nuts 8 having threaded engagement with the screw-threaded portions of the rods 5, as seen in Fig. 2, while adjustable on the upper threaded portions of these rods are the

5 nuts 9, see Figs. 1 and 2, between which and shoulders 10 on the tubular bearings are springs 11, as shown in Figs. 1 and 2, it being readily understood that the compressive effort of these springs may be regulated or adjusted by means of said nuts as circumstances may require.

10 Journaled in the upper and lower bearings 6 and 7 are shafts 12 and 13, respectively, see Fig. 2, and each of these shafts carries a feed roller, the rollers 14 and 15 constituting the upper feed rolls, and the rollers 16 and 17 constituting the lower feed rolls, it being noted that there are two pairs 15 of such feed rolls upon opposite sides of the central vertical line of the machine, so that there will be four rollers upon each side of the point where the knives are located.

20 These feed rollers may be actuated in any suitable way, this construction not forming a part of the present invention although we have shown a convenient way of imparting motion to these feed rolls. Such 25 arrangement is shown in Figs. 1, 2, 8 and 9, wherein it will be seen that the shafts 18 and 19 project beyond the top housing or cap plate 4 and are mounted in suitable bearings 20 on the base 1, the shaft 18 being 30 shown as provided with a pulley 21 to be revolved from any suitable source of power, while upon the said shaft 18 is a gear 22 meshing with a larger gear 23 on the shaft 13 and this in turn meshing with a large gear 24 on the upper shaft 12, see Fig. 2, while upon the shaft 19 is a gear 25 meshing with a large gear 26 on the shaft 13 of the other set of feed rolls and these in turn meshing with a gear 27 on the upper shaft 40 12 of one of the feed rolls.

At the other end of the machine similar gearing is provided, as seen in Figs. 1, 8 and 9, wherein 28 is a gear on the shaft 18 meshing with the gear 29 on the shaft 45 13 of the lower roll, which, in turn meshes with the gear 30 on the shaft 12 of the upper feed roll. The shaft 19 carries a gear 31 meshing with a gear 32 on the shaft 13 of the lower roll and this in turn is in mesh 50 with a gear 33 on the shaft 12 of one of the upper feed rolls.

The shafts 18 and 19 carry the sprocket wheels 34 and 35, respectively, as seen best in Fig. 1, and around these passes the 55 sprocket chain 36 as seen in Figs. 1 and 9, whereby motion is simultaneously imparted to the two sets of upper and lower feed rolls. It is evident, however, that any other suitable form of gearing may be employed for imparting the desired motion to the feed rolls.

It is to be understood that the invention is in no wise restricted to the number of knives employed, the number depending

upon the character of the work and the size 65 or desired capacity of the machine. The construction, disposition and arrangement of the knives being the same, a detailed description of one set, upper and lower, is 70 deemed sufficient.

Referring to Figs. 2 and 3, 37 is the upper knife bar and 38 the lower knife bar. These are secured to the castings or standards 3 in any suitable manner as by bolts or the like 39, it being noted that these knife bars 75 or heads are supported in opposition to each other, leaving a space 40 therebetween, as seen best in Fig. 3, for the passage of the stock or material 41 to be slotted by the knives, and the upper face 42 of the lower 80 knife bar constituting a rest or support for the material in its passage through the machine, as will be clearly understood by reference to Figs. 2 and 3, so that the material is supported against the cut of the upper 85 knife or knives during its passage through the machine.

43 is the upper knife holder and 44 the lower knife holder. These knife holders have dovetailed engagements as at 45 with the knife heads or bars, as seen clearly in Figs. 2 and 3, the upper end of the upper holder having the projecting lug 46 and the lower holder having the projecting lug 47 for the reception of screws or the like 48, 90 as seen clearly in Fig. 3, thus permitting the knife holders to be adjusted lengthwise of the knife bars and held in such adjusted position by means of the set screws or the like 48.

49 is the upper slitting knife and 50 is the lower slitting knife. Each knife is provided with a longitudinal slot 51 for the reception of a bolt 52 provided with a nut 53 thus permitting vertical adjustment of 105 the knife.

54 is a knife cap bearing against the knife and against which the nut 53 bears, it being understood that the bolt 52 passes through said cap as will be readily seen upon reference to Fig. 7. It will be evident that provision is thus made for the adjustment of the knives to and from each other as circumstances may require. Upon reference to Fig. 3 it will also be observed that the upper 115 and lower knives are disposed in angular position with relation to each other instead of being disposed substantially vertically, in order to give better results and a cleaner cut to the material.

120 It is thought that the operation of the machine will be readily understood from the foregoing and that a further detailed description thereof is not necessary. Fig. 3 illustrates the passage of the material 125 through the machine the same being supported upon the upper face of the lower knife bar and the material being firmly

gripped and reliably fed through the machine by means of the two sets of upper and lower feed rolls.

Modifications in detail, proportions and relative arrangement of parts may be resorted to without departing from the spirit of the invention or sacrificing any of its advantages.

What is claimed as new is:

- 10 1. In a veneer slitting machine, a supporting frame, feed mechanism, upper and lower slitting means and upper and lower slitter-carrying means supported in opposition to each other with a space therebetween for the passage of the material to be slit, the upper face of the said last-named means constituting the only support for the material in its passage between the upper and lower slitting means.
- 20 2. In a veneer slitting machine, a supporting frame, feed mechanism, upper and lower slitting means and upper and lower slitter-carrying means supported in opposition to each other with a space therebetween for the passage of the material to be slit, the upper face of the said last-named means constituting the only support for the material in its passage between the upper and lower slitting means, said slitting means being angularly adjustable to and from each other.
- 30 3. In a veneer slitting machine, a support, feed mechanism, independent, spaced-apart upper and lower slitting means, the lower head thereof constituting the only support for the material against the cut of the upper slitter and forming a guide for such material.
- 40 4. In a veneer slitting machine, a base, a top housing, uprights connecting the same and upper and lower slitting knives and knife-bars connecting and supported from said uprights, the upper face of the lower knife-bar forming the only support for the material as it is slit by the said slitting knives.
- 50 5. In a veneer slitting machine, a support, upper and lower slitting knives, feed rollers upon opposite sides of said knives, the upper end of the lower knife head forming the only support for the strip of material passed between said knives against the cut of the upper knife.
- 60 6. In a veneer slitting machine, a support, independent spaced-apart upper and lower slitting knives, and feed rollers in

multiple upon opposite sides of said knives, the upper end of the lower knife head serving as the only support for the material against the cut of the upper knife.

7. In a veneer slitting machine, a support, upper and lower slitting knives, and feed rollers in multiple upon opposite sides of said knives, the upper end of the lower knife head serving as a bed plate to support the material against the cut of the upper knife, said upper and lower knives being adjustable vertically and transversely.

8. In a veneer slitting machine, a support, upper and lower slitting knives, and feed rollers in multiple upon opposite sides of said knives, the upper end of the lower knife head serving as a bed plate to support the material against the cut of the upper knife, said upper and lower knives being adjustable vertically and transversely independently of each other.

9. In a veneer slitting machine, a frame embodying standards, knife heads extended transversely of the frame and connecting said standards, and upper and lower slitting members carried by said heads and disposed substantially vertically to act upon opposite faces of the material, the upper end of the lower knife head forming a bed plate for the support of the material to be slit.

10. In a veneer slitting machine, a frame embodying standards, knife heads extended transversely of the frame and connecting said standards, upper and lower slitting members carried by said heads and disposed substantially vertically to act upon opposite faces of the material, the upper end of the lower knife head forming a bed plate for the support of the material to be slit, and feed rollers upon opposite sides of the knives, the said bed plate being the only support for the material between the rollers.

11. In a veneer slitting machine, a frame embodying standards, members joining the opposed standards and bracing the same, upper and lower knives disposed substantially vertically and disposed in angular position with relation to each other, the upper end of the lower knife support constituting the only bed plate for the support of the material while it is being slit.

In testimony whereof we affix our signatures.

JAMES C. DOZIER.
JOSEPH L. WALKER.
